DRIVING MECHANISM FOR PHONOGRAPHS AND THE LIKE

Filed Oct. 21, 1922

UNITED STATES PATENT OFFICE.

MORRIS H. BENNETT AND HENRY C. ROCHELLE, OF WATERBURY, CONNECTICUT, AS-
SIGNORS TO SCOVILL MANUFACTURING COMPANY, A CORPORATION OF CON-
NECTICUT.

DRIVING MECHANISM FOR PHONOGRAFS AND THE LIKE.

Application filed October 21, 1922. Serial No. 595,970.

This invention relates to certain improvements in electric driving mechanism for phonographs and the like.

With an electrical motor drive for phonographs and the like certain requirements are necessary or desirable. The driving mechanism must drive the turntable or other record carrying support with a substantially constant speed under varying loads, 10 that is, for instance, the difference in load, arising when the needle is at different points respecting the outer circumference of the record. The structure must be such that the mechanism, when running, is noiseless so 15 that the tones produced by the record are not impaired by noise or hum due to voltage changes, or other causes. The mechanism should be capacitated to operate on either an alternating or a direct current circuit, and 20 must have a motor speed adjustable within a limited range. Furthermore, the speed of the turntable or other record support must be substantially constant irrespective of sudden changes in the voltage of the current 25 delivered to the motor. Furthermore, in the best constructions the drive should be such that it may be run on currents having widely different voltages.

It is the especial object of the invention to 30 produce an improved electrical driving mechanism for phonographs and the like in which the power element is an electric motor, which will take care of these requirements. It is a further object of the invention to 35 produce a structure in which a current supply varying widely in voltage may be used without necessitating any changes in the motor or in the driving mechanism operated thereby. It is also an object of the invention 40 to produce a construction in which variations in the motor speed due to voltage changes in the current are automatically taken care of, so that a constant speed is delivered to the turntable or other record support and the motor is prevented from racing 45 due to excessive voltage changes.

With these and other objects not specifically referred to in view, the invention consists in certain novel parts, arrangements 50 and combinations which will be described in detail in connection with the accompanying

drawings and the novel features thereof pointed out in the claims hereunto annexed.

In the drawings—

Figure 1 is a vertical sectional view partly 55 broken away of the improved driving mechanism;

Figure 2 is a detail partly sectional view taken on line 2—2 of Fig. 1;

Figures 3 and 4 are detail partly sectional 60 and partly broken away views showing different positions of the clutch mechanism employed for keeping constant the speed transmitted to the turntable or other support.

Referring now to these drawings—the 65 driving mechanism is in the best constructions enclosed in a substantially dust-proof casing indicated at 1. This casing is supported in any suitable manner, as by being suspended from the underside of the top 70 board 3 of a phonograph cabinet, the casing being secured in any suitable manner as by screws 4, and washers 2 interposed between the top board and the upper side of the casing 1. 75

Mounted to rotate above the top board 3 is a record support which in the particular construction illustrated, includes a flat table 5 of the usual type having a depending socket 6 in which is fixedly secured a driving spindle 7, this spindle taking bearing at its other end in a plate 8 fast on the inside of the bottom 9 of the casing 1, before referred to. This spindle is provided with a worm gear 10 through which it is driven by means of 80 85 connections hereinafter referred to.

The driving connections will include an electric motor. This motor in constructions embodying the invention in its best form is a series wound motor so that it will be universal, that is, will run on either a direct current or an alternating current without change so that the mechanism may be employed with circuits furnishing current of either kind without necessitating any 90 95 changes in the mechanism.

As frequently happens in a circuit of either kind, the voltage in the circuit may vary, which variation would cause a change in the speed of the motor and a consequent 100 change in the speed of the mechanism operated from the motor. In accordance with

the invention, means are provided whereby this change in speed is controlled so that the driving speed delivered to the driving spindle of the turntable is substantially constant under varying loads.

While this may be accomplished in various ways, in the preferred construction, and as shown, there are preferably employed two motor speed controlling devices, one of which acts directly on the motor itself and the other of which employs a governor controlled clutch by which a very fine control or adjustment of the motor speed is effected. In the particular construction illustrated for effecting this, and referring first to the control acting directly on the motor there is shown a motor having an armature 12 rotating between field pieces 13, 14, mounted in any suitable manner in casing 1 as on bolts 15. The armature 12 is mounted on a fixed armature shaft 16 by means of a sleeve indicated at 17 so that the armature may have a small longitudinal movement with respect to the field, on this shaft. This sliding movement of the armature on the shaft is caused by the magnetic flux which, when the current is turned into the motor, causes a movement of the armature with respect to the field. The armature is, therefore, mounted on the axle so that normally the armature is positioned outside the plane of the maximum magnetic flux of the field, and the magnetic pull tends to slide the armature in the plane of the maximum flux.

This movement of the armature is controlled by a stop and this stop is, in the best constructions, arranged to act as a brake so that, if the voltage increases above normal working conditions, the armature will be drawn against this stop and roughly "braked", whereby the motor will be prevented from overspeeding.

In the best constructions, furthermore, this stop will be adjustable so that the motor speed may be varied within certain limits. While this may be effected in various ways, in the construction illustrated where a clutch is employed for effecting a fine adjustment for the control of the motor speed, the armature shaft is provided with one member 18 of a cone clutch. This clutch is provided with a flange 19 adapted to engage with a suitable stop and brake member 20. The clutch member 18 is secured to revolve with the armature and is formed in the particular construction illustrated, with a hub 21 secured to the armature sleeve 17 by means of screws 23.

The brake member may be in the form of a block, the face of which may be covered if desired with any suitable braking material. This brake block is secured on an arm 24 rising from a rock shaft 25 journaled in bearings 26 in the bottom 9 of the casing 1 before referred to. The braking block is,

as before stated, in the best constructions adjustable with respect to the flange 19 with which it engages, so that it may occupy a position nearer or farther away from the flange so as to permit a greater or less movement of the armature, and consequently a greater or less speed of the armature shaft before the braking function takes effect. While this may be accomplished in various ways, in the particular construction illustrated the rock shaft 25 has connected thereto a bent rod 26 having a turned end 27 forming an abutment. By moving the rod up or down the rock shaft 25 may be rocked to vary the position of the brake block 20. This manipulation of the rod 26 may be easily and conveniently effected by means of an adjusting screw 28 provided with a milled head 29, this adjusting screw working in a socket 30 provided in the top board 3 before referred to of the phonograph cabinet, and the rod is rocked against a spring 300 which holds the rod in adjusted position. With this construction a simple adjustment of the brake block may be provided.

In accordance with the invention means are provided for effecting a fine and accurate speed control or adjustment from the motor to the turntable spindle. In the particular embodiment of the invention illustrated, this includes a clutch comprising the clutch member 18 before referred to, having a recess 31 in its face with which co-operates a cone clutch member 32 having a leather face 33. This cone is provided with a hub 34, provided with a sleeve 35 mounted on a short shaft 36 so that the cone can have a sliding movement on the shaft toward and from the recessed clutch member 18. Co-operating with this cone clutch is a governor for controlling the engagement of the clutch members. As shown this governor is a spring governor comprising flat springs, three of these springs being shown, marked 37, 38 and 39. These springs are secured at one end of the hub 34 before referred to and at their other ends are secured to a block 40 secured on the shaft 36 by set screw 40', the springs being secured to the hub and block in any suitable manner as by screws 41. These springs have secured thereto weights 42, one weight being secured to each spring. As the speed goes up the weights 42 spread the springs apart and act to pull the clutch longitudinally of the shaft and causes a slip or disengagement between the cone 32 and the clutch member 18.

The short shaft 36 is provided at one end with a worm 43 which engages with the worm wheel 10 before referred to on the driving spindle 7 of the turntable 5 and acts to drive the spindle at a constant speed.

This shaft 36 may be supported in any suitable manner. In the best constructions, however, the shaft is supported so that a

slight adjustment between the worm and the worm wheel may be provided to take up for wear in the parts. In the particular construction illustrated the shaft is supported at one end in recess 44 in the end of the armature shaft 16 before referred to. At its other end the shaft is supported in a plug 45 having an eccentric recess 46. This plug extends through a hub 47 formed at the end of the casing 1 and is provided with a milled head 48 so that the plug may be given a rotary movement in the hub. The plug is kept from rotation by means of a set screw 49 passing down through a hollow 15 tapped in the hub 47 before referred to.

Means will be provided for oiling the spindle and the armature shaft which may be of any suitable and desired character. In the best constructions, however, these 20 means will be such as to be effective for long periods with but one oiling. In the particular construction illustrated, the end wall of the casing 1 through which the armature shaft 16 passes, is provided with a recess; 25 in which is set a block of felt or other suitable oil-absorbing material 50, this block being held in place by a plate 51. Oil is supplied to this felt block by means of an oil port 52, preferably passing diagonally 30 through a hub 53 formed on the end of the casing 1. With this construction sufficient oil is supplied to the shaft, the rotation of the shaft causing the oil to pass along the same, and to effect a suitable lubrication 35 thereof.

The spindle 7 is or may be lubricated in a similar manner. As shown there is provided a block 54 suitably supported, as on shoulders 55, formed on the top wall of the 40 casing 1, this block acting as an upper bearing for the driving spindle 7, before referred to. This block is provided with a recess 56 in which is set a felt block 57 to which oil is supplied through an opening 58 surrounding 45 the spindle 7.

In machines embodying the invention in its best form means will be provided whereby the driving mechanism and motor may be employed with circuits having power 50 current of widely varying voltages. For instance, the motor and drive may be arranged for a circuit carrying 32 volts. It may be desirable to use the same machine on a circuit carrying 110 volts or a circuit carrying 55 220 volts. This is effected by providing a mounting for a fuse block arranged on a part of the casing where it is readily accessible so that by removing and inserting suitable resistances the mechanism may be employed with wide voltage variations such as referred to. In the particular construction illustrated, there is provided a pair of the usual fuse clips 60, 61, secured to the bottom of the casing by binding posts 62 and 63. 60 As before stated, the motor is wound in

series and the current is passed through a resistance indicated at 64, mounted in the fuse clips or blocks 60, 61.

In Fig. 1 is shown diagrammatically a circuit for the motor including an entering 70 wire 65, this wire passing into the casing through a binding post 66 to the field coil 13. From the field piece 13 the current passes through brush 67, commutator 68, brush 69, field coil 14, binding post 62, resistance 64, binding post 63 and out through wire 70.

The operation of the mechanism is believed to be clear from the foregoing, but for completeness the following may be added—

It may be stated that the parts are set so that the mechanism will properly function at a motor speed of say 20% below the normal voltage that should be supplied from 85 the power source, the slip of the clutch taking care of the difference from normal voltage. The parts are also made of sufficient weight so that the momentum will take of any momentary drop in voltage below 90 the 20% minimum. When the machine is started the governor is relied on to determine the speed at which the table runs, the governor acting to keep this speed constant. As the speed goes up the governor 95 operates the clutch and causes a slip between the clutch members when the motor goes overspeed so that the actual driving speed transmitted from the motor to the spindle remains substantially constant. The 100 motor armature is run at a speed as great or greater than the governor, the stop controlling this speed to a certain extent. For an excess of voltage the stop is brought into greater braking engagement with the motor 105 armature due to the increased magnetic pull on the armature, and acts to prevent the motor from racing at greatly excessive speeds.

While the invention has been described in 110 what is believed to be its best embodiment, it will be understood that various changes may be made in the construction shown and described without departing from the invention and that the invention as regards certain of its features is not to be restricted to a motor construction in which the armature has a slight movement relatively to its field.

What we claim is:

1. In a driving mechanism for phonographs and the like, the combination of a record support, an electric motor, means for controlling any substantial fluctuation in the motor speed due to variations in voltage only, a clutch driven from the motor, a governor controlling the engagement of the clutch members, and connections from the clutch for driving the record support.
2. In a driving mechanism for phonographs and the like, the combination of a record support, an electric motor, means for controlling any substantial fluctuation in the motor speed due to variations in voltage only, a clutch driven from the motor, a governor controlling the engagement of the clutch members, and connections from the clutch for driving the record support.

- graphs and the like, the combination of a record support, an electric motor having its armature normally outside the plane of the maximum magnetic flux of the field, devices co-operating with the armature to control fluctuations in its speed due to variations in voltage only, a clutch mechanism driven therefrom, a governor controlling the engagement of the clutch members, and connections from the clutch for driving the record support. 6. In combination, a driving motor, a driven shaft, a clutch therebetween, means associated with the motor and controlled by variations in the voltage supply to control the resulting variations in motor speed, and means associated with the driven shaft to control the clutch connections upon variation of the speed of the driven shaft whereby a uniform speed of motor and shaft is maintained. 41
3. In a driving mechanism for phonographs and the like, the combination of a record support, an electric motor having a sliding armature normally outside the plane of the maximum magnetic flux of the field, a brake for the armature and co-operating therewith to control speed fluctuations due to variations in voltage only, a clutch mechanism driven from the motor, a governor controlling the engagement of the clutch members, and connections from the clutch for driving the record support. 7. In combination, a turntable, a motor for driving said turntable, means to regulate the speed of the motor in accordance with variations in voltage only, means to regulate the speed of the turntable, means to cause the turntable regulating means to regulate the speed of the turntable independently of the motor regulating means, and means to cause the motor regulating means to regulate the speed of the turntable. 53
23. In a driving mechanism for phonographs and the like, the combination of a record support, mechanism for driving the support, an electric motor, means for effecting a control of fluctuations in the motor speed due to variations in voltage only, and separate means for effecting an accurate control of the support driving mechanism. 8. In combination, a driving shaft having a motor armature mounted thereon, field coils disposed about said shaft, said armature being normally outside the maximum magnetic field created by said coils, means to permit said armature to slide longitudinally into and out of said maximum field in response to variations in voltage only, and means coacting therewith to control the speed of said motor, a driven shaft, a clutch connecting said driven shaft with said driving shaft, governor means on said driven shaft to control the engagement of said clutch whereby the speed of said driven shaft may be further controlled. 75
35. In a driving mechanism for phonographs and the like, the combination of a record support, mechanism for driving the support, an electric motor, means actuated by voltage changes for effecting a control of fluctuations in the motor speed due to variations in voltage only, and separate means for effecting an accurate control of the support driving mechanism. 5. In testimony whereof, we have hereunto set our hands. 76
- 40.
